UNITED STATES PATENT OFFICE

1,931,295

PUMP OPERATING MECHANISM

Arthur C. Nelson, Alexandria, Minn.

Application February 28, 1931. Serial No. 519,221

11 Claims. (Cl. 74—14)

This invention relates to pumps and more particularly to the operating mechanism of those pumps in which the piston is fixed and a lifting pipe reciprocates with relation to the piston, such pumps being shown in my Patent No. 1,802,827, granted on April 28, 1931 and in a pending application filed of even date therewith, Serial No. 519,220.

The object of the present invention is to provide a power operated mechanism for operating pumps of this character which is very simple, which is effective and in which the weight of the string of tubing which constitutes the lift pipe is counterbalanced by a counterweight operating within guides.

A further object is to provide means for lubricating the driving mechanism and operating said driving mechanism in a bath of oil and to provide means whereby the lubricant may be applied to the different bearings of the pump.

Other objects will appear in the course of the following description.

My invention is illustrated in the accompanying drawings, wherein:

Figure 1 is a side elevation of a pumping mechanism constructed in accordance with my invention, the enclosing casing or housing of the pumping mechanism being in section and the lubricant tank being in section;

Figure 2 is a section on the line 2—2 of Figure 1; Figure 3 is a section on the line 3—3 of Figure 1;

Figure 4 is a section on the line 4—4 of Figure 5;

Figure 5 is a section on the line 5—5 of Figure 1.

Referring to these drawings, 10 indicates a pit having a bedding 11 of concrete therein and 12 indicates the sills of a frame. Extending upward from those portions of the sills which extend across the pit 10 are the uprights 13 and extending upward from the forward ends of the sills are the uprights 14.

As illustrated in Figure 4, the sills support longitudinal members 15 upon which the bearings for the crank shaft 16 are disposed, this crank shaft having the crank 17. Mounted upon this crank shaft is a relatively large gear wheel 18 meshing with a pinion 19 of a power shaft 20 which is mounted in suitable bearings upon the members 15. This power shaft is shown as carrying upon it a band wheel 21 whereby the power may be applied to the shaft 20 and thus trans-

mitted to the shaft 16.

Pivotedly supported upon the sills 12, as shown in Figure 4, is a walking beam support 22, the lower ends of which are forked and are formed with bearings 23 for a shaft 24 mounted in bear-

ings 25 on these sills 12. The upper end of the

walking beam support is forked at 26 and the walking beam 27 has a downwardly extending lug 28 inserted in the fork 26 and pivotally engaged therewith by the pivot pin 29. This walking beam may be of any desired shape. It is preferably provided, however, on its under face with two lugs 30 and 31 whereby it may be pivotally connected to a connecting rod 32, see Figure 1, which in turn is engaged with the crank 17. Thus the walking beams are reciprocated.

The connecting rod 32 may be connected either with the ears 30 or 31 as desired. The rear end of the walking beam as shown in Figure 2 is formed with a lug 33 engaged with the forked upper end of a link 34. This link in turn at its lower end is pivotally connected to ears 35 bolted or otherwise attached to the counterweight 36. This counterweight is preferably formed in two sections held together by the bolts 37. The counterweight operates within the pit 10. The counterweight has laterally projecting ears 38 traveling upon vertical guide rods 39. The lower ends of these rods are embedded in the concrete 11 while the upper ends of the rods extend through a cross bar 40 attached by screws or otherwise to the uprights 13. It will thus be seen that the counterweight is guided in a rectilinear path as the walking beam moves up or down. There is thus no swinging action to the counterbalanced weight which would be the case were the weight not guided.

The opposite end of the walking beam, as shown in Figure 3, is pivotally connected to a cross head 41, the cross head having upwardly extending ears 42 supporting the pivot pin 43 which extends through the forward end of the walking beam. The cross head 41 is guided by the vertical guide rods 44. The lower ends of these rods are mounted in a cross brace 49 flanges at its ends and attached by screws or otherwise to the uprights 14 and the upper ends of the guide rods 44 are engaged with a cross piece 50 flanged and supported on the upper ends of the uprights 14 by means of screws or bolts passing into these uprights. The pump body or discharge chamber is designated 51. A stuffing box 52 having the usual gland is mounted at the upper end of this chamber and a stuffing box 53 is provided at the lower end of the chamber. The chamber is provided with a spout 54 seen in Figure 1.

Operating through the stuffing box 52 is a connecting rod 55 having screw-threaded engagement at its upper end with the cross head 41. The lower end of this rod 55 has screw-threaded

105

110

engagement with a coupling 56 and this in turn has screw-threaded engagement with a vertically reciprocating lift tube 57 which passes through the gland 53.

5 As shown in Figure 3, the lift pipe 53 carries at its lower end a cylinder 58. Having telescopic engagement with this cylinder is a stationary piston 59 indicated in detail, this mechanism being fully shown, described and claimed in my 10 pending application for patent of even date here-with, Serial No. 519,220. The piston 59 it may be explained has an anchoring means thereon whereby the piston is engaged with the lining of the well and is held from any vertical movement and as the lift pipe 57 reciprocates, water will be pumped upward through the lift pipe and discharged into the chamber 51 through an outlet 60 formed in the coupling 56.

Supported in any suitable manner upon the 20 sills 12 is a lubricant containing receptacle or tank 61 having a bottom, side walls and end walls held together in any suitable manner. The end and side walls extend upward to a point slightly above the bearings for the crank shaft 25 16 and the shaft 20. This tank is to be more or less filled with oil so that these parts including the gear wheels 18 and 19 will run in oil and so that the bearing for the post or walking beam support 22 will also be lubricated by this oil. 30 Braces 62 and 63 extend upward from this tank to the upper ends of the uprights 13 and 14.

Extending entirely over this pumping unit and entirely enclosing it is an outer casing 64 shown most clearly in Figures 1, 2 and 3 which may be 35 supported in any suitable manner, as for instance, by being bolted as shown in Figure 1 at its forward end to flanges 65 and at its rear end by being bolted to the ends of the sills 12.

This casing entirely encloses the operating 40 mechanism. It may, of course, have means whereby access may be had to the interior of the casing. As a matter of fact, however, the mechanism is so simple and so carefully lubricated that there is no necessity of access being had to 45 the interior of the casing under ordinary circumstances.

The vertical members 13 and 14 are shown as 50 connected by longitudinally extending braces 66. Disposed above the outer casing are lubricant holding tanks 67, 68 and 69. The tank 67 has a downwardly discharging spout 70 which extends through the casing and discharges directly upon the pivotal connection of the walking beam with the cross head as shown in Figure 3. The tank 55 69 has a spout 71 discharging directly downward on to the pivotal connection of the rod 34 with the cross head.

Mounted upon the walking beam is a lubricant 60 containing trough 72 which oscillates with the walking beam and the spout of the tank 69 discharges into this trough. From this trough extend pipes 73, 74 and 75. The pipe 73 discharges oil directly downward on to the pivotal connection between the walking beam and its supporting member 22 as shown best in Figure 4 where the pipe 73 is shown as extending into and through the walking beam. The pipe 74 extends downward and into the walking beam in the same manner as the pipe 73, but discharges upon 70 the pivotal connection between the connecting rod 32 and the walking beam. The pipe 75 forms a like function for the pivotal connection which may be used between the ears 31 and the connecting rod 32. This pipe, under ordinary circumstances, of course, is stopped unless the

connecting rod 32 is connected to the ears 31. The surface oil, of course, will drip down into the tank 61. As the walking beam oscillates, the oil in the trough 72 will surge backward and forward so that all the pipes 73, 74 and 75 are 80 supplied with oil.

The main object of the casing 64 is, of course to protect the mechanism from dust and dirt and to keep out foreign matter from the oil tank. The bottom edge of the casing 64 is secured to the frame by machine screws at different points. At the pumping end of the machine, this casing is cut out where it fits around the pump barrel 51 or body of the pump, the upper edge of this cut-out portion resting on the flanges at the upper edge of this body as shown most clearly in Figure 1. The casing, of course, may have any convenient opening in the detachable cover for the purpose of inspection, supplying lubricant oil to the tank as it may be needed. From Figure 95 4 it will be seen that the sills 12, the posts 14, the supporting members 15 and the bottom and front wall of the lubricant containing tank are cast in one piece or these parts may be welded together. Then, as shown most clearly in Figure 100 5, the side walls 61a and 61b of the tank are fastened by screws or otherwise to the uprights 14 and at their rear ends are joined by a rear wall 61c. The side walls 61a are so formed as to accommodate the gears 18 and 19. Therefore, 105 the bottom sills and the superposed sills 15 and the posts 14 with the forward and rear end walls are cast and formed at one time and afterwards machined as to the bearings for the crank shaft and pinion shaft and the surfaces for the side 110 wall of the gear case 61a and the side plate 61b. No wood is used whatever. The bottom 61d of the oil tank is also cast integral with the sills 12 and with the front and rear plates or walls of the tank. Preferably also the rear post 14 will 115 be cast as an integral part of the sills 12. This construction provides a very solid base and support for the pumping mechanism and causes the tank to act to brace the two sills against any movement toward or from each other and also 120 acts to brace the uprights 14.

It will thus be seen that the oil tank attains two objects, that of holding oil for the gears and bearings and of bracing the structure.

This is important for the reason that this part 125 of the tank serves thus a two-fold purpose. It not only contains oil, but it acts as a brace between the elements of the frame. The bearings, of course, will be lubricated by keeping the oil in this tank at a level such that these parts are 130 partly or entirely submerged in oil.

It will be seen that by reason of the fact that the weight of the lift pipe is fully balanced by the counterweight 31, and the parts are thus evenly balanced, that the engine will drive this 135 pump with a minimum of power, the only power needed being sufficient to raise the weight of the water that is contained within the lift pipe and, of course, to overcome friction. All the parts are carefully housed, protected and lubricated. It will be seen that the mechanism is 140 very simple and yet effective.

I claim:—

1. In a mechanism of the character described, a hollow body, vertical posts on each side of the 145 hollow body, braces extending across said posts, one of said braces being extended adjacent the tops of the posts and the other engaging the hollow body, vertical bolts connecting said braces on each side of the hollow body and acting as 150

guides, an operating rod extending into the hollow body, a cross head carrying said rod and having sliding engagement with the vertical bolts connecting the braces, a walking beam operatively connected to the cross head and pivotally supported for oscillation and means counterbalancing the moving parts connected to the opposite end of the walking beam, and power operated means for reciprocating the walking beam.

10 2. A pumping mechanism of the character described, comprising a tubular body, an operating rod extending downward through the tubular body, vertical frame members extending up on each side of the body, upper and lower braces connecting the vertical members, the lower brace being engaged with and supporting the body, vertical guide bolts connecting said braces, a cross head mounted upon the operating rod and having sliding engagement with said bolts, a walking beam pivotally connected to the cross head at one end, a counterweight connected to the other end of the walking beam, vertical guides for said counter-weight, the support for the walking beam pivoted at its lower end and at its upper end pivoted to the walking beam, said support oscillating in the plane of the walking beam and power operated means for oscillating the walking beam.

30 3. A pump mechanism of the character described, including a tubular body, a supporting frame including two uprights disposed on each side of the tubular body, braces rigidly connecting said uprights, vertical bolts passing through said braces on each side of the tubular body and constituting guides, a rod operating within the tubular body, a cross head slidable upon said bolts and operatively connected to the operating rod, sill beams constituting part of said frame, a walking beam, a supporting member pivoted upon said sill beams for oscillation toward or from the body, a walking beam pivotally supported upon the upper ends of said supporting members and operatively connected at one end to the cross head, vertical members forming part of the frame on each side of the other end of said walking beam from the tubular body, a transverse brace connecting the upper ends of said members, vertical guide rods passing downward through said brace and anchored at their lower ends, a counterweight slidably engaged by said guide rods and having linked connection to the rear end of the walking beam, and power driven operating mechanism mounted upon said frame and operatively connected to the walking beam.

55 4. A pump mechanism of the character described, including a supporting frame having two uprights, braces rigidly connecting said uprights, laterally spaced vertical bolts passing through said braces and constituting guides, a cross head slidable upon said bolts and operatively pivoted to the operating rod, sill beams constituting part of said frame, a walking beam, a supporting member pivoted upon said sill beams for oscillation toward or from the guides, a walking beam pivotally supported upon the upper ends of said supporting members and operatively connected at one end to the cross head, vertical members forming part of the frame on each side of the other end of said walking beam from the pump body, a transverse brace connecting the upper ends of said members, vertical guide rods passing downward through said brace and anchored at their lower ends, a counterweight slidably engaged by said guide rods and having linked connection to the rear end of the walking beam, power driven

operating mechanism mounted upon said frame and operatively connected to the walking beam, and a lubricant containing tank having its bottom disposed between the sill beams and at its forward and extending over the sill beams and disposed between said upright members on each side of the pump body, the sides of the tank being disposed exterior to said sill beams and attached thereto and attached at their forward ends to said uprights, and gear supporting beams extending parallel to the sill beams to which the upper ends of the sides of the tank are connected, the rear wall of the tank being connected to the bottom of the tank and to the sides of the tank and extending over the sill beams, and operating gearing carried by the gear supporting beams and enclosed within the tank.

5. In a pumping mechanism, laterally disposed longitudinally extending sills having uprights at one end, a pump body supported upon said uprights, supporting members mounted upon the first named sills adjacent said uprights and having bearings, a crank shaft and a pinion shaft mounted in said bearings, gears mounted upon said shafts and engaging each other, a walking beam disposed above the shafts and operatively connected at one end to the pump body, a counter-weight operatively connected to the other end of the walking beam, posts integral with and extending upward from the sills, guides carried by said posts and upon which said counter-weight operates, and an oil tank having a bottom, front and rear walls integral with the sills and having lateral sills attached at their forward ends to the uprights and at their rear ends to the rear end wall.

6. In a mechanism of the character described, a walking beam, a support to the upper end of which the walking beam is pivoted, said support being pivoted at its lower end for movement in the plane of the walking beam, a reciprocatable member pivotally connected to one end of the walking beam, a weight operatively connected to the other end of the walking beam and counter-balancing the weight of the reciprocatable member, power operated means for oscillating the walking beam, and vertical, rigid guides with which the reciprocatable member has operative engagement, said guides causing the reciprocatable member to move in a right line direction.

7. In combination, a walking beam, a vertical support upon which the walking beam is pivoted, means pivotally supporting the lower end of the support for movement in a direction parallel to the length of the walking beam, a cross head to which one end of the walking beam is pivoted, rigid vertical guides with which the cross head has sliding engagement, the guides acting to guide the adjacent end of the walking beam in a vertical, rectilinear line, rigid vertical guides disposed at the rear end of the walking beam, a counter-weight having sliding operative engagement with said guides, a rigid link pivotally connecting the counterweight to the adjacent end of the walking beam, and power operated means for oscillating the walking beam.

8. In combination, a walking beam, a vertical support upon which the walking beam is pivoted, means pivotally supporting the lower end of the support for movement in a direction parallel to the length of the walking beam, a cross head to which one end of the walking beam is pivoted, rigid vertical guides with which the cross head has sliding engagement, the guides acting to guide the adjacent end of the walking beam in

a vertical, rectilinear line, rigid vertical guides disposed at the rear end of the walking beam, a counter-weight having sliding operative engagement with said guides, a rigid link pivotally connecting the counter-weight to the adjacent end of the walking beam, power operated means for oscillating the walking beam, comprising a power driven shaft having a crank and a link pivotally connected to the crank and pivotally connected to the walking beam at a point between the walking beam support and the cross head.

9. In combination, a walking beam, a support for the walking beam pivoted at its upper end thereto, means pivotally supporting the lower end 15 of the support for movement in a plane parallel to the length of the walking beam, rigid vertical guides disposed at the forward end of the walking beam, rigid vertical guides disposed at the rear end of the walking beam, rigid connections 20 between the upper ends of said guides, a cross head connected to the forward end of the walking beam and having sliding engagement with the first named guides, a counter-weight having sliding engagement with the second named 25 guides, a rigid link connecting the counter-weight to the rear end of the walking beam, and power driven means for operating the walking beam including a crank shaft, and a link pivotally connecting the crank of the shaft to the walking beam between its point of pivotal connection to the support and its point of pivotal connection to the cross head.

10. A pumping mechanism of the character described including a walking beam, a walking beam support pivotally mounted at its lower end 30

for movement in the plane of the walking beam and to the upper end of which the walking beam is fulcrumed intermediate the ends of the beam, a counter-weight, a rigid connecting rod pivotally connected to the counter-weight and to the beam 80 adjacent one end thereof, vertical rigid guides for the counter-weight, vertical rigid guides for the opposite end of the walking beam, a rod pivotally connected to this end of the walking beam, and means for oscillating the walking beam connected to the walking beam between the fulcrum thereof and the last named rod.

11. A pumping mechanism of the character described including a walking beam, a walking beam support pivotally mounted at its lower end for movement in the plane of the walking beam and to the upper end of which the walking beam is fulcrumed intermediate the ends of the beam, a counter-weight, a rigid connecting rod pivotally connected to the counter-weight and to the beam 90 adjacent one end thereof, vertical rigid guides for the counter-weight, vertical rigid guides for the opposite end of the walking beam, a rod pivotally connected to this end of the walking beam, and means for oscillating the walking beam connected to the walking beam between the fulcrum thereof and the last named rod, and including a crank shaft having a gear wheel, a pinion engaged with the crank shaft, a power operated shaft upon which the pinion is mounted, a lubricant 95 containing tank within which the gear wheels, the shafts thereof and the lower end of the walking beam supports operate, and means for supplying oil to said tank.
